W. H. HONSBERGER.
ELECTRIC SWITCH.
APPLICATION FILED JULY 30, 1917.

1,256,692.

Patented Feb. 19, 1918.

UNITED STATES PATENT OFFICE.

WILLIAM HENRY HONSBURGER, OF WELAND, ONTARIO, CANADA, ASSIGNOR OF ONE-
THIRD TO GEORGE C. BROWN, OF WELAND, ONTARIO, CANADA.

ELECTRIC SWITCH.

1,256,692.

Specification of Letters-Patent. Patented Feb. 19, 1918.

Application filed July 30, 1917. Serial No. 183,609.

To all whom it may concern:

Be it known that I, WILLIAM HENRY HONSBURGER, of the town of Welland, in the county of Welland and Province of Ontario, Dominion of Canada, have invented certain new and useful Improvements in Electric Switches; and I hereby declare that the following is a full, clear, and exact description of the same.

10 This invention relates to a switch, which may be used in connection with an electric lighting apparatus for vehicles, to selectively control the circuits for the illumination of the headlights and the non-illumination 15 of the auxiliary light, the dimming of the headlights and the non-illumination of the auxiliary light, and the dimming of the headlights and the illumination of the auxiliary light, this electric lighting apparatus comprising a switch-controlled main lighting circuit, a shunt resistor circuit connected with the main lighting circuit, and a switch-controlled auxiliary lighting circuit connected with the main lighting circuit, whereby the closing of the main lighting circuit for the brilliant illumination of the main lights will open the auxiliary lighting circuit, and the closing of the auxiliary lighting circuit for the brilliant illumination 25 of the auxiliary light will open the main lighting circuit and shunt part of the current through the resistor for the dimming of the main lights, and the opening of the main and auxiliary lighting circuits 30 will shunt the current through the resistor for the dimming of the main lights and the non-illumination of the auxiliary light.

35 This invention relates more particularly to the specific construction of the switch, which is provided with a movable switch blade and two fixed contacts or poles, located at opposite extremities of the oscillation of the switch blade, so that the switch blade, when in contact with one of said poles, will close the circuit for the illumination 40 of the headlights and the non-illumination of the auxiliary light, and when in contact with the other pole, will close the circuit for the illumination of the auxiliary light and the dimming of the headlights, and when in a neutral position between said poles, will open the auxiliary lighting circuit 45 for the non-illumination of the auxiliary light and the dimming of the head-

lights by the shunt current passing through 55 the resistor.

The invention further relates to a coupling means forming part of the switch, by which it can be secured to the steering post of the vehicle, as hereinafter set forth and particularly pointed out in the claims.

In the drawings:

Figure 1, is a diagrammatic view illustrating the arrangement of circuits;

Fig. 2, is a front elevational view showing 65 the switch secured to a steering post;

Fig. 3, is a side elevational view of the parts shown in Fig. 2;

Fig. 4, is a detail view of the switch, showing 70 the switch blade and fixed contacts;

Fig. 5, is a rear view of the parts shown 75 in Fig. 4;

Fig. 6, is an end sectional detail view of the parts shown in Fig. 4, to show the fixed contacts and the insulator between them;

Fig. 7, is a cross-sectional view of the 80 switch blade;

Fig. 8, is a detail view of one of the switch case parts;

Fig. 9, is a detail view of the other of the 85 switch case parts and one of the semi-cylindrical coupling members; and,

Fig. 10, is a detail view of the other semi-cylindrical coupling member.

Like characters of reference refer to like 90 parts throughout the specification and drawings.

a represents the source of current, which may consist of a storage or other battery. *b* represents a conductor leading from the 95 source of current *a* to the contact *c'* of the main switch *c*. *d* represents a conductor leading from the contact *c''* of the main switch *c* to the contact *e* of the control switch. *g* represents a conductor leading 100 from the contact *h* of the control switch to the lamps *i* of the headlights *j*. *k* represents the return conductor from the lamps *i* to the source of current *a*. *l* represents a conductor leading from the contact *m* to the lamp *o* of the auxiliary light *p*. *k'* represents a return conductor leading from the lamp *o* of the auxiliary light to the return conductor *k*, and *r* represents a resistor in shunt to the conductors *d* and *g*.

For the operation of the lighting apparatus, the main switch *c* is closed, so that the current may circuit from the source *a*, con-

- ductor *b*, switch *c*, to the conductor *d*. When the switch blade *f* is in a neutral position between the contacts *h* and *m*, the auxiliary light *p* is cut out and the current passes 5 from the conductor *d*, by means of the resistor *r*, conductor *g*, headlight lamps *i*, and return conductor *k*, to the source of current, the headlight lamps, during this circuit, being dimmed to the extent of the resistance 10 offered by the resistor *r*.

When the switch blade *f* closes the circuit from the contact *e* to the contact *h*, the current passes from the conductor *d*, by means of the switch *f*, conductor *g*, lamps *i* of the 15 headlights *j*, and return conductor *k*, to the source of current, this being the direct circuit from the source of current *a* to the lamps *i* of the headlights *j*, and which, when closed, renders the resistor inoperative and 20 cuts out the auxiliary lighting circuit, so that the full strength of the current may be utilized for the brilliant illumination of the headlight lamps.

When the switch blade *f* is moved to close 25 the circuit from the contact *e* to the contact *m*, part of the current is shunted from the conductor *d* through the resistor to the conductor *g*, and the remainder of the current passes from the conductor *d*, by means of 30 the switch blade *f*, contact *m*, and conductor *l*, to the lamp *o* of the auxiliary light *p*, returning from the lamp by means of the conductor *k'*, to the return conductor *k*, this 35 circuit brilliantly illuminating the auxiliary lamp and dimly illuminating the headlights.

To provide for the necessity of rapidly changing these circuits, during the travel 40 of the vehicle, to either brilliantly illuminate the headlight lamps or to dim the headlight lamps without illuminating the auxiliary light, or to dim the headlight lamps and brilliantly illuminate the auxiliary light, I have so constructed the control 45 switch that a single movement of the switch blade will effect the desired change in the circuits, and I have particularly designed this control switch so that it can be adjustably connected to the steering post of a motor vehicle to enable the driver to manipulate the switch blade without removing his hands from the steering wheel.

With this purpose in view, the control switch consists of an insulated base *f''*, in 50 which the contacts *e*, *h* and *m* are set, and provided with the usual binding posts *e'*, *h''* and *m''*, respectively, for the conductors *d*, *g* and *l*. On the contact *e*, is oscillatingly mounted the switch blade *f*, this switch blade being provided with an insulated handle *f''* extending beyond the insulated base *f''*.

Overhanging each of the contacts *h* and *m*, is a spring leaf *h'* and *m'*, respectively, 65 to engage the switch blade *f* and press it

against the contacts *h* and *m* when in engagement therewith.

As shown in Fig. 6, the spring leaves *h'* and *m'* are of a U-bend formation, and the contacts *h* and *m* are connected to them, the 70 spring leaves being of conducting material, so that there will be a double contact with the switch blade when in engagement therewith.

As shown in Fig. 4, the contacts *h* and *m* 75 are located near the opposite edges of the insulated base *f''*, and between these contacts is an insulator *f⁴*, having between the contacts a substantially V-shaped recess *f⁵*, to receive a corresponding projection *f⁶* on the 80 switch blade *f*, the purpose of the recess *f⁵* and the projection *f⁶* being to prevent the inadvertent movement of the switch blade when in a neutral position, the necessity of this prevention arising from the jarring and 85 jolting of the car tending to cause the movement of the switch blade.

In closing the switch, is a switch case, comprising two separable members *q*, *q'*. The member *q*, to which the switch is appropriately secured by bolts *z*, consists of a plate of shape and dimensions corresponding to the back of the insulated base *f''*, and along each side edge of the switch case member *q* are inturned flanges *r* partly overlying its 95 front surface. The switch case member *q'* is of corresponding shape and dimensions to the insulated base *f''*, and the edges *q''* of its sides *q''* are outwardly flared to engage under the inturned flanges *r* of the switch case 100 member *q*, to maintain the assembly of these parts.

As shown in Fig. 3, the top of the switch case is open, and when the switch is 105 enclosed within the switch case, an unoccupied space is provided between the front of the switch case member *q'* and the insulated base *f''*, for the freedom of movement of the switch blade *f* between the contacts *h* and *m*.

Connected to, or integrally formed with, 110 the switch case member *q*, is a semi-cylindrical coupling member *s*, to partly embrace the steering post *t⁴* and formed in the coupling member *s* are three sets of slots *s'*, *s''*, *s³*, parallel with the axis or the meeting edges 115 of the coupling member, the row of slots *s'* being adjacent to the meeting edge *s⁴*, with the remaining rows of slots arranged between the row *s'* and the switch case member *q*, the opposite meeting edge *s⁵* being flanged 120 and provided with holes for the clamping bolts *s⁷*.

Coöperating with the coupling member *s*, is a corresponding coupling member *t*, having at one of its meeting edges, hook-shaped lugs *t'* to engage through the slots of any row in the coupling member *s* and separably connect the two coupling members.

By means of the several rows of slots *s'*, *s''*, *s³*, the coupling, consisting of the two 130

coupling members *s* and *t*, can be increased or reduced in diameter to the approximate diameter of the steering post, or, in other words, the diameter of the coupling is readily adjustable to permit of the attachment of the switch to any of the standard sizes of steering posts.

The edge *t''* of the coupling member *t* is flanged and provided with holes *t^s*, corresponding with the holes *s^t*, to receive the clamping bolts *s'* by which the flanged edges of the coupling members are secured together.

By means of this construction, a simple and convenient means for attaching the switch to the steering post is provided.

Having thus fully described the nature of my invention, what I claim as new and desire to secure by Letters Patent, is:—

20 1. An electric switch to be attached to the steering post of a vehicle, comprising fixed and movable contacts, and a case therefor having an adjustable coupling consisting of two semi-cylindrical members to encircle the 25 post, one of which is provided with a plural-

ity of rows of slots parallel with its meeting edges, and the other of which is provided with hook-shaped lugs along one meeting edge to engage in the slots of any of said rows.

2. In an electric switch to be attached to the steering post of a vehicle, comprising fixed and movable contacts, and a case therefor consisting of a case member having a body part with inturned flanges along its side edges, and a case member having a body part with outwardly flaring sides to be engaged by the inturned flanges of the other case member, and an adjustable coupling consisting of two semi-cylindrical members one 35 of which is provided with a plurality of rows of slots parallel with its meeting edges, and the other of which is provided with hook-shaped lugs along one meeting edge to engage in the slots of any of said rows.

Welland, July, 1917.

WILLIAM HENRY HONSBURGER.
